UNITED STATES PATENT OFFICE.

JOSEPH L. ROUSSEAU, OF BROOKLYN, NEW YORK, ASSIGNOR TO MERGENTHALER LINOTYPE COMPANY, A CORPORATION OF NEW YORK.

ART OF MANUFACTURING MATRICES.

1,422,137.

Specification of Letters Patent.

Patented July 11, 1922.

Application filed August 1, 1921. Serial No. 488,866.

To all whom it may concern:

Be it known that I, JOSEPH L. ROUSSEAU, a citizen of the United States, residing at Brooklyn, in the county of Kings and State 5 of New York, have invented certain new and useful Improvements in the Art of Manufacturing Matrices, of which the following is a specification, reference being had therein to the accompanying drawing.

10 My invention relates to two-character matrices, such as are used in commercial linotype machines for the casting of type bars or slugs. In the manufacture of these matrices, it is the practise to rout out a portion of their operative edges, or more specifically, to cut transverse notches or recesses therein, and then to punch the matrix characters in the bottoms of said notches. Under this practise, and especially in the 15 case of the larger characters or those having accents or descenders, the partition which separates the adjacent notches frequently stands below the operative edge of the matrix, this condition arising from the fact 20 that the partition is dragged down below its proper position by the displacement of the metal during the punching operation. As a result, in casting, the separating partition fails to fit up tightly against the mold 25 and hence permits the molten metal to escape from the notch of the active character into the notch of the inactive character, thereby producing an imperfect slug and giving rise to other serious objections.

30 My present invention is directed to an improvement in the method of manufacture by which the foregoing objections may be avoided. This improvement, specifically, involves first, the provision of a blank with 35 a raised portion on its character edge occupying the zone intermediate the two character zones; next, the cutting out of the usual notches in the two character zones, which operation removes such parts of the 40 raised portion as lie within said zones but which leaves that part of the raised portion lying within the intermediate zone on the partition separating the two notches; then, the punching of the matrix characters in the 45 bottom walls of said notches in the customary way; and thereafter, the dressing down of the raised portion to bring the separating partition flush with the edge of the blank. In other words, the scheme is to punch the 50 matrix characters in the edge of a blank 55

having a raised portion between adjacent characters, and thereafter to dress down said raised portion flush with the edge of the blank. As a result of this procedure, any drawing down of the separating partition 60 during the punching operation will be fully compensated for by the raised portion, which may thereafter be dressed down to the edge of the blank without difficulty. In this way, when the matrix is finally completed, the separating partition is caused to seat tightly up against the mold during the casting operation and thus to seal the molten metal against escape from the particular character-containing notch in registration with the mold slot.

While my invention has been herein illustrated in connection with a matrix having only two characters, it should be understood that it is equally applicable to matrices having a greater number of characters.

Referring to the drawings:

Figs. 1 to 4 show on an enlarged scale a matrix in different stages of manufacture; and

Fig. 5 is a perspective view of the matrix in its final form.

The first step of my improvement consists in providing a blank A, such as shown in Fig. 1, having on its character edge a 85 raised portion B, which is designed to occupy the zone intermediate the two character zones and irrespective of the size of the matrix characters. As is obvious, the character zones will be wider and the intermediate zone narrower for larger characters or those having accents or descenders than for the smaller characters or those having no accents or descenders. Blanks having raised portions of different extents could be 90 used for the different sizes of matrix characters, but it is preferred to employ a single form of blank as above indicated. The blank A may be produced in any suitable manner, as for instance in a die-press.

The second step consists in forming in the edge of the blank A (e. g. by a routing operation) notches C located within the two character zones see Fig. 2. This operation removes such parts of the raised portion 105 B as lie within the character zones but leaves intact that part lying within the intermediate zone, so that, after the routing operation, the raised portion remains alone upon the partition D which separates the notches 110

C. These notches are of the customary depth, although they may be of any desired depth.

The third step consists in punching the 5 matrix characters E in the bottom walls of the notches C, as illustrated in Fig. 3. In the drawing, the partition D has been indicated as drawn down to a slight extent by the punching operation, but it will be observed that the raised portion B still stands 10 above the edge of the blank notwithstanding such displacement of the partition.

The fourth and last step of my improvement consists in dressing down the raised 15 portion B (by milling or otherwise) so as to bring the separating partition D flush with the edge of the blank, as shown in Fig. 4.

It may be explained that my improvement 20 deals only with one phase of manufacture and that various other operations, in addition to those described, must be performed on the blank, to bring it to its final form as shown in Fig. 5. These operations are well 25 known to those skilled in the art and require no mention.

As before stated, the effect of my improvement is that the separating partition between 30 two adjacent character-containing notches is caused to emerge from the manufacturing process with its outer face flush with the operative edge of the matrix, thereby insuring the proper engagement of the partition with the mold during the slug 35 casting operation.

While I have set forth the several steps which I propose to follow, these steps might be variously modified as to sequence or otherwise without departing from the spirit of 40 my invention. I therefore desire it to be understood that I do not limit myself to any specific mode of procedure except in so far as such limitations are specified in the claims.

Having thus described my invention, what 45 I claim is as follows:—

1. In the art of manufacturing plural-character matrices, providing a blank with a raised portion on its character edge occupying the zone intermediate two adjacent 50

character zones, punching the matrix characters in their respective zones, and thereafter dressing down the raised portion to the edge of the blank.

2. In the art of manufacturing plural-character matrices, providing a blank with a raised portion on its character edge occupying the zone intermediate two adjacent character zones, forming notches in said character zones while leaving in the intermediate zone a separating partition whereon the raised portion remains, punching the matrix characters in the bottom walls of said notches, and thereafter dressing down the raised portion to bring the separating partition flush with the edge of the blank. 55 60 65

3. In the art of manufacturing plural-character matrices providing a blank with a raised portion on its character edge of sufficient extent to occupy the zone intermediate two adjacent character zones irrespective of the varying widths of said zones, 70 punching the matrix characters in their respective zones, and thereafter dressing down the raised portion to the edge of the blank. 75

4. In the art of manufacturing plural-character matrices, providing a blank with a raised portion on its character edge of sufficient extent to occupy the zone intermediate two adjacent character zones irrespective of the varying widths of said zones, 80 forming notches in said character zones while leaving in the intermediate zone a separating partition whereon the raised portion remains, punching the matrix characters in the bottom walls of said notches, 85 and thereafter dressing down the raised portion to bring the separating partition flush with the edge of the blank.

5. In the art of manufacturing plural-character matrices, punching the matrix characters in the edge of a blank having the portion intermediate two adjacent characters rising above said edge, and thereafter dressing down the intermediate portion flush 90 with said edge. 95

In testimony whereof, I have affixed my signature hereto.

JOSEPH L. ROUSSEAU.
